PROCESS AND APPARATUS FOR SEPARATING INTERMIXED DIVIDED MATERIALS

Richard Peale and Rembrandt Peale, Jr., St. Benedict, Pa., assignors, by mesne assignments, to Peale-Davis Company, Wilmington, Del., a corporation of Delaware

Application September 23, 1930
Serial No. 483,857

21 Claims. (Cl. 209—489)

The invention relates to a novel and useful process and apparatus for separating intermixed, divided materials, varying relatively greatly in size, and in certain of its features, the invention has special adaptation to the purification of unsized coal representing difficult problems of purification.

Objects and advantages of the invention will be set forth in part hereinafter and in part will be obvious herefrom, or may be learned by practice with the invention, the same being realized and attained by means of the instrumentalities and combinations pointed out in the appended claims.

15 The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a side elevation of a form of mechanism adapted for use in carrying out the invention;

Fig. 2 is a detached plan view of the sub-areal air chamber structure beneath the table;

Fig. 3 is a transverse, vertical section taken through Fig. 1, substantially on the line 3—3 of Fig. 1;

Fig. 4 is a top plan of a table constructed in accordance with the invention;

Fig. 5 is a view similar to Fig. 4, and showing the preferred arrangement of variable spacing of the separating partitions and of the sub-areal air chambers beneath the deck;

Fig. 6 is a vertical longitudinal section taken on line 6—6 of Fig. 5; and

Fig. 7 is a top plan of a table, showing a system of air zoning applied thereto, and omitting the separating partitions.

The invention comprises a novel and highly efficient separating process of the type wherein lifting and loosening air currents and vibratory motion coact on the intermixed particulate or divided materials to effect separation thereof. Our process, and the preferred mechanism for practicing it, are especially adapted to efficiently separate, usually in a single processing, intermixed materials which vary relatively greatly in the size range of the pieces or particles; and also materials of the kind or condition stated presenting further difficulties in that the specific gravities of the intermixed materials are very close.

The process is especially applicable to, and finds a wide field of usefulness in, the purification of raw, unsized coals, many of which present great difficulties of the kind indicated. In purifying unsized coal, that is run-of-mine coal, in which only the very large lumps have been crushed or removed (to avoid damage to the mechanism), the size of the coal varies from fine dust to pieces several inches in dimensions, and the slate, rock, sulphur, and other intermixed impurities, likewise often vary through an equally wide range of sizes. In many such coals the relative specific gravities of the coal and impurities vary relatively little, and the gravitational splitting point between the clean coal and the lightest impurities is very close. Certain coals present further difficulties by reason of the relative proportions of the fine and coarse materials, a very high proportion of either rendering efficient purification exceedingly difficult. In other coals great difficulties are due to the presence of a very high proportion of impurities in the very fine materials.

The present invention even in purifying such difficult materials as raw coals of the kind described, and possessing the refractory characteristics stated, obviates the great amount of mechanism, time and labor required for preliminary sizing as usually practiced, and the subsequent use of as many separating tables as there are sizes of coal thereby produced; which have generally been regarded as essentially prerequisite to the purification of any raw or impure coal, and likewise avoids the resultant great breakage of the coal.

In our present novel process the raw or impure coal is regulably fed to constitute a continually-advancing bed, which, as it advances over an air-permeable deck, is progressively stratified and thereby separated and purified, through the action of lifting and loosening and floating air currents and the vibration and inclination of the bed. In addition, preferably, quick and unimpeded fractional removal is effected of the impurities as they separate out and settle upon the deck, while mechanical support or sustentation is provided for the larger and large floatant pieces of coal, and consequent thereon ready and free discharge of the finer impurities. By these coacting novel actions, forces and conditions, the separation of unusually difficult unsized coals is rendered practically efficient and complete, usually in a single process operation on one table.

By the main features of the present invention there is effected free and unimpeded passage for

the pieces of settled impurities of all sizes, along the deck and from the bed, without wedging or choking, and concurrently therewith is effected auxiliary sustentation of the larger pieces of 5 flotant purified coal and of the ever thickening stratum or stream of forwardly flowing purified coal.

In the commercial practice of our invention, and carrying out these stated objects or features, 10 the inter-spacing of the separating partitions, that is, the paths or passages along which the settled impurities are impelled from the bed are variably proportioned in different parts of the bed to conform to, and to freely accommodate, 15 the size of impurities settling on any particular part of the table. That is, in that part of the bed or table where the largest impurities settle, the separating partitions are spaced apart sufficiently to permit the largest pieces of impurities 20 to slide along between the separating partitions without wedging or choking. The separating partitions are gradually spaced closer together along the table, proportionally as the finer and finer impurities settle, giving for each gradually 25 decreasing size of settled impurities only sufficient inter-space to permit free and unimpeded passage from the bed without wedging or choking.

Concurrently with this described action or 30 step, auxiliary mechanical sustentation is imparted to the large pieces of flotant coal and thereby to a large part of the forwardly moving and gradually thickening superior coal stratum or stream. This auxiliary sustentation is effected by the same variable regulation of the 35 separating partition interspaces. As these become narrower, they still permit the free, sliding transverse passage of the relatively small pieces of impurities while the relatively large flotant 40 coal pieces cannot settle between the separating partitions, but many of them engage with and slide across the top edges of the separating partitions, and thus directly or indirectly impart 45 auxiliary support to the entire forwardly moving stratum of purified coal, which is at the same time flotant upon the air currents.

In accordance with certain features of our 50 invention, and in the present preferred commercial practice thereof, it is carried out with a bed of the materials that in passing over a vibrating deck or table is subjected to lifting, loosening and floating air currents which vary gradually, or by steps, between greatest and least intensity. 55 To effect this varying air current intensity we preferably utilize a zoning or gradation of the air perviousness of the table. For most materials we preferably use the air currents of greatest intensity at the rear of the bed, the intensity decreasing gradually forwardly.

60 Further, in the present preferred practice we maintain a transversely inclined bed, from which the heavy impurities, as soon as they settle from the bed onto the deck, are impelled diagonally toward and out of the upper side edge of the bed, there being thus effected a continuous fractional discharge of the settled impurities, the larger pieces of which settle out at the rear and by gradually decreasing sizes forwardly along the table to a minimum at or near the front end 65 of the bed. Thus a concentration of the separated heavy materials within the bed is avoided. In such a bed, the superior stratum of purified coal flows freely forwardly along the bed, growing in volume and thickness, and to a large degree larger pieces tend toward the bottom of

said stratum, with some possible tendency toward remixture. With a bed and general process of the kind described, the separating partitions at the rear of the bed and table will be spaced apart sufficiently far to permit the largest pieces of impurities to slide freely along therebetween, and they will be gradually set closer together forwardly along the table, spaced apart throughout only sufficiently to permit the free passage behind them of the impurities settling at that particular point on the table. Thus, the two steps or functions of our process, as already described, namely, free discharge of the impurities of all sizes, and the auxiliary mechanical sustentation of the larger pieces of coal, especially in areas of lesser air current intensity, is effected.

In practicing the process in the form or manner just indicated, the strong air currents forced through the rear of the bed provide a loosening action sufficiently intense to cause the largest pieces of the heavy impurities, together with some of the finer heavy material, to rapidly settle on the deck, and as the passages between the separating partitions are adequate, these large settled impurities slide along freely behind the separating partitions, without wedging or choking, and are discharged, preferably approximately immediately, from the side edge of the bed. Just above these, at this part of the smaller impurities, some only a little smaller, and a large part of the coal are still in intermixture and are flotant in the strong air currents, and the entire bed is moving forwardly. Immediately forward of the rear of the bed, pieces of the impurities next 105 smaller in size settle out of the bed onto the deck, due to the slight decrease in the air current intensity and the naturally slower settling of finer particles in the rising air currents, and the interspaces or passages between the separating partitions, although narrower, are sufficiently wide to permit that size of impurities to slide along freely behind them to discharge at the side edge of the bed. This action continues forwardly 110 along the table, the impurities of lesser and lesser size settling upon the deck due to the lesser and lesser intensity of the air currents. The interspaces or passages between the separating partitions, along which the impurities slide transversely to discharge, are narrower and narrower 115 progressing forwardly along the bed, conformably to the gradual decrease in size of the settling impurities, and yet permitting free sliding of the impurities from the bed as already described.

Forwardly from the rear of the bed, the coal 120 gradually forms as a flotant stratum, which at first contains also the finer heavy impurities sustained in intermixture. As the superior flotant stratum progresses freely forwardly the intermixed finer impurities are progressively settled 125 and eliminated as hereinbefore described, whereby the flotant superior stratum continuously grows in purity. Due to the areas of gradually lessening air intensity and the elimination of the bulk of the impure material in the inferior settled 130 stratum, the larger and heavier pieces of coal are brought nearer to the bottom of the bed and would normally tend to sink behind the separating partitions except for the harmonic relation which our invention maintains between the 135 gradually changing conditions of the bed and the separating partition interspaces. That is, before the conditions just mentioned might obtain in the bed, the inter-spaces or passages between the separating partitions have become sufficiently 140

narrow that the larger pieces of coal, mostly at the bottom of the flowing stratum of purified coal, are too large to sink between the separating partitions and so they slide along forwardly over the transversely-extending top edges of the partitions at the same time being largely supported by the air currents. Due also to this auxiliary mechanical sustentation of the coal stratum, the finer refuse, now settled, is not interfered with in its free sliding to discharge behind the relatively closely set separating partitions. Thus, remixture of the previously separated materials is prevented, and if there is still remaining intermixiture of fines, their separation is facilitated by the absence of large pieces of coal, as the relatively weak air currents will lift the fine coal particles over the separating partitions to move forwardly with the bed, while the fine impurities will move along the intervening passages to discharge at the side edge of the bed of materials.

To further facilitate and maintain the separation and purification especially of the difficult materials previously described, and in realization of the various main objectives stated, namely, to facilitate the rapid and easy discharge of all sizes of the settled rock in all parts of the bed, and the auxiliary mechanical sustentation or safeguarding of the larger pieces of floatant coal and of the gradually purifying stratum of coal, we gradually proportionately decrease the height of the separating partitions forwardly in a definite relation to the decreasing size of the separating pieces or particles, and the corresponding increase in the thickness of the stratum of pure coal forwardly along the bed. This, in most embodiments, would comprise a gradated decrease in the height of the separating partitions in harmony with the decrease in the interspaces of the separating partitions. Such a construction is shown in Fig. 6 of the drawings. Thus the interposition of the auxiliary mechanical sustaining action occurs at successively lower points forwardly along the bed, but at heights everywhere so that the largest pieces of refuse will pass unimpededly out of the bed and the stratum of floatant pure coal will move unmixed forwardly to discharge at the front of the bed.

Referring now in detail to the present preferred manner of carrying out our novel process, and to a mechanism adapted for carrying it out, same is exemplarily disclosed and described in connection with a table of the type shown in the copending application of Richard Peale, Ser. No. 389,722, filed August 31, 1929, although so far as concerns the main features of the invention, it may be practiced with other kinds and constructions of tables.

The means for maintaining the bed of materials, and progressing it forwardly, for vibrating the bed and forcing the lifting and loosening air currents therethrough, may be of any known or suitable form, so far as concerns many features of the present invention.

In the exemplary embodiment thereof, a table is shown having an air-pervious deck 1, which is preferably transversely-inclined upwardly in the direction of travel of the settled heavy impurities and preferably also forwardly in the direction of travel of the superior floatant stratum of coal. This deck is supported on a suitable vibratable or reciprocable frame which is pivotally mounted at either side upon two series of backwardly and upwardly-inclined pivoted arms 6. The lower ends of the arms 6 are in turn pivotally mounted upon a stationary frame 11, which also consti-

tutes the frame for the lower non-vibrating part of the air chamber. This frame comprises side and end members, and is longitudinally variably inclinable for the purpose of longitudinally inclining the bed of materials. Accordingly, it is shown pivotally mounted at its rear end 12, and along either side it is supported by a series of screw rod supports 13 and 14, of any known or other suitable form. These supports may be turned to vary the longitudinal inclination of the frame 11 and therewith of the table deck 1 upon which the forwardly-progressing bed of materials is supported. The pivoted supporting arm 6 renders the deck 1 and its associated parts longitudinally vibratable or reciprocable upon the tiltable frame 11. The table vibrating means may be of any desired or convenient form, and as shown, an eccentric 15 is fixed to rotate on a shaft 16, and a rod 17 is connected at one end to the eccentric and at its other end to the rear end of the table. Thereby the desired reciprocatory movement is imparted to the table.

Means are provided for maintaining upon the table a forwardly-progressing bed of substantial thickness of the raw coal, or other material undergoing separation or purification. Means for maintaining such a bed is shown more or less diagrammatically as including a hopper 18, a variable speed feed-out device 19, and a chute 20 for delivering the raw coal, in variably regulated quantity, to the rear end of the bed on table 1.

The means for providing the loosening and lifting air currents and forcing same upwardly through the bed may likewise vary widely in form and structure, and as shown, an air chamber 29 is supported in the frame 11, and this air chamber is connected to the vibrating table structure by a flexible air-tight juncture 30. At its rear end, chamber 29 communicates by a flexible connection 31 with the duct 32 of a fan 33. Suitable regulating devices may be provided if desired, and as shown herewith a series of rotatable or pivoted valves 34 may be provided in the chute 32; and additional or other air current regulating means may be employed, as desired.

The separated and settled refuse is preferably discharged from the table by the shortest and quickest route. As embodied, the table is supplied with a plurality of refuse-discharging boxes 41, arranged along one of the side edges of the table, as shown and described in certain of our copending applications, and in those of Kenneth Davis. Thus the settled impurities are impelled diagonally across the table and are expelled from the side edge of the bed. The discharge boxes 41 are located along the side of the upper bed-retaining wall of the table, and an air header 44 receives air from the fan chute, or the rear part of the air chamber, and the air from the header 44 is supplied by flexible conduits 46 to the refuse boxes 41. This acts to insure discharge of the rock and other impurities only, and to prevent discharge of coal, in a known manner.

The form of table or deck 1 which we preferably employ in carrying out our invention is shown in plan in Figs. 4 to 7. This table is relatively long and narrow and has a rear bed-retaining wall 47 and side bed-retaining walls 48 and 49. The spillage edge 50 for the purified coal is preferably diagonally arranged at the forward end of the table, and preferably occupies a very large proportion of the length of the table. This gives a very long spillage edge for the purified coal and at the same time permits a protracted period for action upon the less readily separable

components or sizes of the intermixed materials. The early purified coal will be discharged from the rear part of the spillage edge 50, but the separating action will be continued forwardly along the bed, in connection with the further separating partitions, while the purified coal is discharged progressively along the spillage edge. The separating partitions in this type of table are forwardly and transversely-inclined, their rear ends starting some against the rear retaining wall 47, others against the side retaining wall 48, and others starting from the spillage edge 50, as will be clear from Figs. 4 and 5.

In accordance with our present invention, the spacing apart of the separating partitions is predetermined for a given table and coal in definite relation to the range of sizes of material treated on the table. That is, the inter-spaces or passages between the separating partitions 51 at the rear part of the table will be made sufficiently wide to permit the largest pieces of impurities in the particular coal being purified, which settle on this part of the table, to pass readily, by friction and inertia, behind the separating partitions to discharge, without wedging or choking. The inter-spaces or passages between the separating partitions are decreased forwardly along the bed in proportion or harmony with the decrease in size of the impurities that settle at the various points along the table, these inter-spaces or passages being determined of just sufficient width to permit free passage behind the separating partitions of the size of impurities which settle on the table at any given or particular point. Thus, the inter-spaces or passages grow narrower and narrower between the separating partitions forwardly along the table, and at some median point on the table, dependent in part upon the size and other characteristics and conditions of the particular coal being purified, the separating partitions begin to function also as an auxiliary mechanical support or sustention for the larger particles or pieces in a superior stratum of purified coal. Proceeding forwardly along the table, the separating partitions are nearer and nearer together, and thus the auxiliary mechanical sustaining action is gradually extended to smaller and smaller pieces of the floatant superior stratum of purified coal. Not only does the auxiliary mechanical sustention act to prevent sinking and remixture of this portion of the purified coal stratum, but it also operates to prevent the larger pieces of coal from settling in the inter-spaces between the separating partitions, and thus unimpeded passage is assured to the relatively small size particles of impurities which have settled on this portion of the deck and are slid to discharge behind the separating partitions. Furthermore, if there is a substantial residue of dirty fines, the separating action is continued on these behind the separating partitions unimpeded by the presence or intermixture of large pieces. Thus, the gradually separating coal fines will rise above the separating partitions and move forwardly to discharge, but the fine impurities will remain behind the partitions and pass transversely to discharge. All these factors or functions cooperate to effect rapid and complete separation and purification of the coal.

The present invention operates advantageously in connection with sub-areal air regulation, preferably throughout the entire bed. A form of sub-areal zoning the same or similar to that shown in some of our earlier copending applications is

preferred. A plurality of sub-areal air chambers 52 are formed directly beneath the air-pervious deck 1, and regulate or settable means for controlling the passage of the air through the individual sub-areal chambers is provided. As shown, 80 the bottom plate 57 of the respective sub-areal air chambers is provided with a plurality of perforations, which may be fitted with stoppers or corks 58 to any desired extent, thereby regulating the air current flow through the particular sub-areal chamber as may be desired. It will be understood, of course, that the form of air-admission control for the sub-areal chambers may be varied as desired.

The character of the lifting and loosening air currents forced through the bed of materials undergoing separation may be widely varied, as may be found desirable or efficient. In the present exemplified embodiment, we have shown a pulsating air current action, such as is disclosed 95 in said copending application of Richard Peale, Ser. No. 389,722, and this need not be described in full detail. For this purpose a rotary butterfly valve or shutter 59 is mounted on a shaft 60, journaled transversely across the air chamber. 100 The shutter or butterfly valve 59 rotating within the chamber, alternately leaves it practically wide open and then closes it practically completely, and correspondingly varies the air action through the bed. The valve actuating means 105 comprises a sprocket chain drive 61, which runs over a sprocket wheel 62, fixed on the shaft 60, and over a sprocket wheel 64, fixed on the shaft 16, already described. By this structure and arrangement, a pulsating action of the air current 110 along the bed may be effected, if desired. If the drive for the shutter 59 is silenced and the shutter removed or left in horizontal position, the same mechanism will provide a steady or uniform air current.

The variation in the spacing of the separating partitions, as an improved constructional feature, is harmonized with the structure and position of the sub-areal chambers, and thereby a very fine regulation of the lifting and loosening air currents in relation to the interspacing between the separating partitions is effected. Such an arrangement is shown in Fig. 5 of the drawings, where the widest interspacing of separating partitions is indicated by numeral 64, and the forward partition wall of the separating partition, inclined in the same direction, is indicated by the broken line 65. The next degree of interspacing between the separating partitions is indicated by 70, and the forward separating wall 130 of the sub-areal chamber is indicated by 71, this wall being inclined in the same direction as the separating partitions. The side walls of the table likewise constitute walls of the sub-areal air chambers, and there may be cross-partitions between such partitions as 65 and 71, as shown in Fig. 2 of the drawings, for the chambers 52. Successive similar arrangements of variations in interspacing of separating partitions and the boundary walls of sub-areal chambers are indicated 140 respectively by the pairs of reference numerals 72, 73 and 74, and 75 and 76.

In practicing our invention, we preferably employ a table deck of gradated or zoned air perviousity, and preferably such a table with the air 145 current intensity decreasing forwardly. In Fig. 7 there is diagrammatically shown a zoning of a table into four degrees of air perviousity, the varying degrees being indicated as A, B, C, and D. It will be understood that the gradations may be 150

more gradual as by varying the number and size of air perforations in the deck plate 1.

It will be clear from the foregoing description, and as already disclosed in prior applications of

- 5 Kenneth Davis and Richard Peale, that the gradations and relative areas of the zones A, B, C, D, etc. will preferably, in practice, be calibrated and dimensioned substantially according to the relative quantities of different sizes of pieces and
 10 particles in the raw coal being treated, and especially the relative quantities of the different sizes of the heavier impurities. For example, when preliminary tests of the run-of-mine coal show a relatively large proportion of coarse heavy
 15 material, the rear zone A of greatest air intensity will be accordingly large in area to provide adequate air action for the stratification of the large quantity of coarse impurities. Correspondingly the other zones of air intensity will be calibrated
 20 and proportioned according to the relative quantities of intermediate and smaller sized impurities in the raw coal.

In the preferred practice of our invention, we likewise calibrate the inter-spaces between the
 25 separating partitions with the relative proportions of different sizes of the materials in the raw coal to be cleaned. For example, if preliminary tests of the raw coal show that a relatively great proportion of the impurities are in the largest sizes, the area of the deck occupied by the
 30 wider inter-spaces will be correspondingly extensive, and similarly when there is a preponderance of fines, the inter-spaces will be narrow along a relatively greater portion of the deck.

35 In many cases the inter-spaces will be calibrated in substantially the same proportions as the zones of air-perviousness. For example, as shown in Figs. 5 and 6, the inter-spaces between separating partitions are arranged in groups of decreasing widths forwardly along the deck, each group occupying an area corresponding to a zone of air-perviousness. It will be understood, however, that the arrangement and grouping of the
 40 separating partition inter-spaces are not necessarily dependent upon or calibrated in accordance with the air-perviousness zones, because with many materials the latter may be determined by factors which do not affect the layout of the inter-spaces.

50 Similarly, as hereinbefore indicated, the heights of the separating partitions may be proportioned and graduated in harmony with the general sequence of the separating process. Preferably, the separating partitions are caused to decrease in height in much the same relation as the decrease in the interspaces between the separating partitions. An exemplary embodiment of this feature is shown in Figure 6, where the heights of the separating partitions are graded down as the interspaces between them also decrease, and it will be understood that the principles of calibrating the heights of the separating partitions with respect to the air control and other features of the process will usually be much the same as those applied to the calibration of the inter-spaces.

55 The invention in its broader aspects is not limited to the specific mechanisms shown and described but departures may be made therefrom within the scope of the accompanying claims without departing from the principles of the invention and without sacrificing its chief advantages.

What we claim is:—

- 55 1. The process of separating intermixed di-

vided materials varying relatively greatly in size, such as unsized run of the mine coal, which comprises forwardly progressing and progressively stratifying and purifying a bed of the materials by vibration and forcing air therethrough, progressing a separated light material as a continuous floatant stratum toward discharge, and effecting auxiliary mechanical sustentation for a coarser part of said separated floatant light material moving toward discharge during the latter stages of separation in the bed. 85

2. The process of separating intermixed divided materials varying relatively greatly in size, such as unsized run of the mine coal, comprising forwardly progressing and progressively stratifying and purifying a bed of the materials by vibration and forcing air therethrough, discharging settled heavy impurities from the side of the bed, flowing the purified coal forwardly along the bed, and effecting mechanical sustentation for the coarser part of the floatant coal after the coarser impurities have been discharged. 90

3. The process of separating intermixed divided materials varying relatively greatly in size, such as unsized run of the mine coal, comprising forwardly progressing and progressively stratifying and purifying a bed of the materials by vibration and forcing air therethrough, discharging settled heavy impurities from the side of the bed at a plurality of points flowing the purified coal forwardly along the bed, and effecting mechanical sustentation for the coarser part of the floatant coal after the coarser impurities have been discharged. 100

4. The process of separating intermixed divided materials varying relatively greatly in size, such as unsized run of the mine coal, which comprises forwardly progressing and progressively stratifying and purifying a transversely inclined bed of the materials by vibration and forcing air therethrough, effecting settlement of the coarser heavy impurities during the earlier stages of separation in the bed, and effecting auxiliary mechanical sustentation for a coarser part of a separated floatant light material moving toward discharge during the latter stages of separation in the bed. 115

5. A mechanism for separating intermixed divided materials varying greatly in size, such as raw run-of-mine coal, including in combination an air pervious table, means for maintaining a forwardly moving bed of the materials upon the table, and means for separating, stratifying and facilitating the discharge of separated materials which comprise devices for vibrating the bed, devices for forcing loosening and lifting air currents through the bed, separating partitions on the table variably spaced apart from widest spacing at the feed end of the table to narrowest spacing at the discharge end for directing settled heavy material freely to discharge by friction and inertia and for affording auxiliary mechanical sustentation to a material floated or sustained by said air currents. 125

6. A mechanism for separating intermixed divided materials varying greatly in size, such as raw run-of-mine coal, including in combination an air pervious table, means for maintaining a forwardly moving bed of the materials upon the table, and means for separating, stratifying and facilitating the discharge of separated materials which comprise devices for vibrating the bed, devices for forcing loosening and lifting air currents through the bed gradated from relatively great intensity at the rear to relatively small 140

intensity at the forward part of the bed, and separating partitions spaced more widely apart in the area of great air current intensity and gradually spaced closer together in areas of decreased air current intensity for directing settled heavy material freely to discharge by friction and inertia and for affording auxiliary mechanical sustention to a material floated or sustained by said air currents.

10. 7. A mechanism for separating intermixed divided materials varying greatly in size, such as raw run-of-mine coal, including in combination an air pervious table, means for maintaining a forwardly moving bed of the materials upon the table, and means for separating, stratifying and facilitating the discharge of separated materials which comprise devices for vibrating the bed, devices for forcing loosening and lifting air currents through the bed gradated from relatively great intensity at the rear to relatively small intensity at the forward part of the bed, and separating partitions spaced more widely apart in the area of great air current intensity and gradually spaced closer together in areas of decreased air current intensity and gradually decreasing in height with the decrease in inter-spacing, for directing settled heavy material freely to discharge by friction and inertia and for affording auxiliary mechanical sustention to a material floated or sustained by said air currents.

8. A mechanism for separating intermixed divided materials varying greatly in size, such as raw run-of-mine coal, including in combination an air pervious table, means for maintaining a forwardly moving bed of the materials upon the table, and means for separating, stratifying and facilitating the discharge of separated materials which comprise devices for vibrating the bed, devices for forcing loosening and lifting air currents through the bed in varying degrees of intensity along the bed, and separating partitions spaced widest apart in the area of greatest air current intensity and spaced gradually closer together in the areas of lesser air current intensity.

9. A mechanism for separating intermixed divided materials varying greatly in size, such as raw run-of-mine coal, including in combination an air pervious table, means for maintaining a forwardly moving bed of the materials upon the table, and means for separating, stratifying and facilitating the discharge of separated materials which comprise devices for vibrating the bed, devices for forcing loosening and lifting air currents through the bed in varying degrees of intensity along the bed, and separating partitions spaced widest apart in the area of greatest air current intensity and spaced gradually closer together in the areas of lesser air current intensity, the separating partitions decreasing in height from areas of great to areas of less air current intensity.

10. The process of purifying raw coal varying substantially in size which comprises subjecting a traveling bed of said coal to a pneumatic stratifying action, regulating the separating forces to effect settlement of different size ranges of heavy impurities in different areas of the bed, and supplying auxiliary mechanical support to the air-floated coal particles after equivalent size ranges of impurities have been settled.

11. The process of purifying raw coal varying substantially in size which comprises progressing a continuous bed of said coal along an air-

pervious support and passing lifting and loosening air currents therethrough, causing progressively smaller sizes of heavy impurities to settle to the support and supplying a progressively increasing auxiliary mechanical sustention to prevent settlement of coal particles equal or greater in size than the settled impurities.

12. The process of purifying raw coal varying substantially in size which comprises progressing a continuous bed of said coal and passing lifting and loosening air currents therethrough, progressively decreasing the lifting action of said currents to effect settlement of progressively smaller particles of heavy impurities, and applying auxiliary mechanical sustention to coarse floatant coal particles in the areas of decreased air action.

13. The process of purifying raw coal varying substantially in size which comprises passing a continuous bed of said coal over zones of different lifting and loosening air intensities, said intensities being calibrated to effect settlement of different predetermined size ranges of heavy impurities, and applying auxiliary mechanical sustention to the floatant coal pieces of greater size than that of the impurities to be settled in a given zone.

14. A mechanism for purifying raw coal of relatively wide size ranges including in combination an air-pervious table, means for progressing a bed of raw coal continuously therealong, means for passing lifting and loosening air currents through the bed, said air currents being of different intensities in different areas of the bed, a plurality of separating partitions for guiding settled heavy impurities along the surface of the table to discharge, the spaces between the separating partitions being greater in the areas of high air intensity and smaller in the areas of low air intensity.

15. A mechanism for purifying raw coal of relatively wide size ranges including in combination an air-pervious table, means for progressing a bed of raw coal continuously therealong, means for passing lifting and loosening air currents through the bed, said air currents being of different intensities in different areas of the bed, a plurality of separating partitions for guiding settled heavy impurities along the surface of the table to discharge, the spaces between the separating partitions being greater in the areas of high air intensity and smaller in the areas of low air intensity, and the vertical extent of said separating partitions varying in substantially the same manner.

16. A mechanism for separating intermixed divided materials including in combination an air-pervious deck, means for feeding raw material to the deck, means for progressing a bed of raw material along the deck from the feed to the discharge means and means for effecting a pneumatic stratification and a separation of the stratified materials including devices for passing air currents upwardly through the bed and a plurality of parallel separating partitions on the surface of the deck for guiding settled heavier material along the deck, said partitions being relatively widely spaced near the feed portion of the deck and being spaced progressively nearer together toward the discharge portion of the deck.

17. A mechanism for separating intermixed divided materials including in combination an air-pervious deck, means for feeding raw material to the deck, means for discharging separated lighter material from the deck, means for

- progressing a bed of raw material along the deck from the feed to the discharge means and means for effecting a pneumatic stratification and a separation of the stratified materials including devices for passing air currents upwardly through the bed and a plurality of parallel separating partitions on the surface of the deck for guiding settled heavier material along the deck, said partitions being relatively widely spaced and of relatively great vertical extent near the feed portion of the deck and being spaced progressively nearer together and of lesser height toward the discharge portion of the deck.
18. In an air-cleaning process for coal or other similar material, containing in intermixture pieces and particles varying relatively greatly in size in which the coal is separated from heavier refuse by lifting the coal on an air cushion above a separating surface in zones of differing air pressure in accordance with the size of coal to be separated, the step of mechanically supporting above the separating surface in each successive zone the coal of sizes too large to be supported by the air cushion in this zone.
19. The process of separating heavier refuse of a certain size from a mixture of coal and refuse of various sizes, consisting in supporting above a separating surface the coal of said certain size, and coal and refuse of smaller sizes, on an air cushion, mechanically supporting above the separating surface coal of larger sizes, and removing the refuse of the certain size which remains supported on the separating surface.
20. The process of separating heavier refuse from a mixture of coal and refuse, consisting in transporting the mixture through a series of zones in which supporting air cushions are provided, the air cushions being of successively decreasing intensity throughout the series, the air cushion in each zone being adapted to support above a separating surface coal of a certain size and all coal and refuse of smaller size, but not to support refuse of the certain size, mechanically supporting above the separating surface in each zone coal of sizes larger than the certain size, and withdrawing the refuse of the certain size which remains supported on the separating surface.
21. In an apparatus for air-cleaning coal or similar material comprising a separating table, means for reciprocating the table, the table having a zoning deck divided into a plurality of diagonally arranged zones, means for supplying air cushions in the zones of gradually diminishing intensity from the supply to the delivery end of the table, and outlet gates of graduated sizes, one for each zone, at one side of the table for permitting the expulsion of refuse therethrough while preventing the escape of coal, a plurality of diagonally positioned parallel riffles on the zoning deck for directing the mixed materials toward the gates, the spacing between these riffles being greater in the zones of greater air pressure and less in the zones of lesser air pressure.
